UNITED STATES PATENT OFFICE.

FRANK. M. BAKER, OF NEW YORK, N. Y., ASSIGNOR TO JULIUS M. COHN, OF SAME PLACE.

CORDING ATTACHMENT FOR SEWING-MACHINES.

SPECIFICATION forming part of Letters Patent No. 445,361, dated January 27, 1891.

Application filed June 30, 1890. Serial No. 357,209. (No model.)

To all whom it may concern:

Be it known that I, FRANK. M. BAKER, of New York, in the county of New York and State of New York, have invented a new Improvement in Cording Attachments for Sewing-Machines; and I do hereby declare the following, when taken in connection with accompanying drawings and the letters of reference marked thereon, to be a full, clear, and exact description of the same, and which said drawings constitute part of this specification, and represent, in—

Figure 1, a plan view of a cording attachment embodying my invention; Fig. 2, a reverse plan view of the forward end thereof; Fig. 3, a view of the attachment partly in side elevation and partly in vertical central section; Fig. 4, a broken plan view of a section of fabric re-enforced with three parallel stay-strips applied under an overlay.

My invention relates to an improved cording attachment for multiple-needle sewing-machines, for use in applying cords or stay-strips to corsets under an overlay, as distinguished from placing them between two thicknesses of fabric, the object being to provide for rightly guiding two or more cords or stay-strips under the overlay, which is at the same time both folded and fed.

With this end in view my invention consists in a presser-foot provided with three or more staggered needle-holes and a cording attachment having a multiple cord or stay-strip guide divided into isolated passages arranged in line with the spaces between the needle-holes in the presser-foot, and in certain details of construction and combinations of parts, as will be hereinafter described, and pointed out in the claims.

As herein shown, the presser-foot A is provided at its rear end with the usual socket B, to receive the presser-bar of the machine, to which the attachment is applied. The said presser-foot has four needle-holes C formed in it to receive as many needles mounted in a multiple-needle head, which is not shown. These holes are arranged out of line with each other or staggered so as to leave space between them, the width whereof determines the separation of the lines of stitching. The forward end of the foot is turned upward, as at D, and

has a folder E, of any approved construction, secured to its under face.

The multiple guide F, which comprises my present invention, is rigidly secured to the under face of the folder and near the lower end thereof. If desired, however, it may be pivotally attached thereto. As herein shown, the guide consists of a flat loop of sheet metal internally divided by two parallel bars G into three separate longitudinal passages respectively arranged in line with the three spaces between the four needle-holes in the presser-foot, so that the guide keeping the cords or stay-strips properly separated will direct them into the said spaces, and hence between the lines of stitching.

Fig. 4 shows a section H of fabric, to which an overlay I has been applied by four parallel rows of stitching J, forming three pockets or cases for as many stay-strips K K K. The number of needle-holes in the presser-foot and the number of isolated passages in the guide may of course be varied according to the number of cords or stay-strips which it is designed to apply at any one time. By making the guide independent of the folder I secure ample room laterally for the arrangement of the passages with respect to the needle-holes and also avoid the interference of material which must result when the cloth and cords are fed in together, and particularly when more than two cords are being used. The particular construction of the multiple guide may of course be varied, nor is it limited to use with a presser-foot and folder of the particular construction shown. I would therefore have it understood that I do not limit myself to the exact construction set forth, but hold myself at liberty to make such changes as fairly fall within the spirit and scope of my invention.

I am aware that a cording attachment for a multiple-needle sewing-machine having a cord-guide located within a folder is not new, and I do not, therefore, broadly claim the combination of a folder and cord-guide.

Having fully described my invention, what I claim as new, and desire to secure by Letters Patent, is—

1. A cording attachment for sewing-machines having a presser-foot provided with three or more staggered needle-holes, a folder

located at the forward end of the presser-foot, and a multiple cord or stay-strip guide constructed with two or more isolated passages respectively arranged in line with the spaces between the needle-holes, the said guide being made independent of the folder and located below the same, whereby ample room for arranging the passages with respect to the needle-holes is secured and the interference and chafing of the fabric and the cords or strips avoided, substantially as described.

2. A cording attachment for multiple-needle sewing-machines having a presser-foot

provided with three or more staggered needle-holes, a folder located at the forward end of the presser-foot, and a multiple cord or stay-strip guide located below the folder and consisting of a flat sheet-metal loop containing two or more parallel bars dividing it into isolated passages respectively arranged in line with the spaces between the needle-holes in the presser-foot, substantially as described.

FRANK. M. BAKER.
